Primary Examiner — Susan Bennett Hattan*Assistant Examiner* — Marie Fast Horse(74) *Attorney, Agent, or Firm* — Robert Brouillette; Brouillette & Partners(57) **CLAIM**

The ornamental design for a fan, as shown and described.

DESCRIPTION

FIG. 1 is a top perspective view of the fan;

FIG. 2 is a first side view of the fan;

FIG. 3 is a second side view of the fan;

FIG. 4 is a front view of the fan;

FIG. 5 is a rear view of the fan;

FIG. 6 is a bottom view of the fan. The broken lines in FIG. 6 depict parts of the fan that form no part of the claimed design; and,

FIG. 7 is a top view of the fan.

1 Claim, 5 Drawing Sheets(56)
